UNITED STATES PATENT OFFICE.

LEWIS C. MYERS, OF NEW YORK, N. Y., ASSIGNOR, BY MESNE ASSIGNMENTS, TO ROYAL TYPEWRITER COMPANY, INC., OF NEW YORK, N. Y., A CORPORATION OF NEW YORK.

ENVELOP AND CARD FEED DEVICE FOR TYPE-WRITING MACHINES.

1,136,034.

Specification of Letters Patent. Patented Apr. 20, 1915.

Application filed June 21, 1912. Serial No. 704,964.

To all whom it may concern:

Be it known that I, LEWIS C. MYERS, a citizen of the United States of America, residing in the borough of Brooklyn, city and State of New York, have invented a certain new and useful Improvement in Envelop and Card Feed Devices for Type-Writing Machines, of which the following is a specification.

10 This invention is shown as applied to the card feeding devices disclosed in the application of Edward B. Hess, No. 644,386, filed August 16, 1911; and in a sense is an improvement thereon, although applicable 15 no doubt to other apparatus designed for the same purpose.

The invention primarily consists in providing means for adjustment of the length of the receptacle to adapt it to receive cards 20 and envelopes of different lengths; and preferably there is an indicator operated automatically by such adjustment to apprise the operator of the standard sizes of envelopes for which the receptacle may be adjusted. 25 Adjustment of the length of the receptacle is made equally at both ends so as not to disturb the symmetrical relation of the contained envelopes to the printing point on the platen of the machine. These features, together with several minor ones are herein-after fully described.

In the accompanying drawing: Figure 1, is a front elevation showing the card receptacle adjusted for envelopes of the greatest length for which it is adapted. Fig. 2, a similar view showing the length of the receptacle reduced to receive envelopes of the shortest length indicated on the scale. Fig. 3, a top plan view of what is shown in 40 Fig. 1. Fig. 4, an elevation of the right hand end of the apparatus; and Figs. 5, 6, 7 and 8 are detail views of the cam device for actuating the envelop feeding lever.

Since the apparatus illustrated is, except 45 with respect to the special features or improvements contemplated by this application, the same in all respects as that disclosed in the above mentioned application of Edward B. Hess, those portions only comprising the improvements will be described in detail.

Within the envelop receptacle 1 are end gage plates 2, 3, movable from the ends to-

ward the center for purposes of adjustment. The bottom edges of the end gage plates 2, 3, may rest and move upon the floor 4 of the receptacle and their front and rear edges are slidable upon or closely adjacent to the front and rear walls of the receptacle. Adjacent the top of the gage plate 3 there is secured on the face thereof adjacent the end wall of the receptacle a strap or plate 5 the projecting rear end of which projects through a horizontal slot 7 in the rear wall of the receptacle as shown by dotted lines 65 in Fig. 1. Just beyond the front edge of the gage plate 3 this strap is turned at right angles and extends across the front parallel with the front wall of the receptacle. This front portion of the strap is marked 8 70 and the portion thereof between the part 8 and the front edge of the plate runs in a slot 9 in the front wall 10 of the box as shown in Fig. 1. The lower edge of the part 8 of the metal plate or strap is for a 75 suitable distance from its end, which extends inwardly beyond the center of the receptacle, formed with rack teeth 11. The gage plate 2 has attached to its outer face a similar strap 12 arranged in all respects 80 the same as the strap 5 and extending horizontally across the front of the receptacle in a plane below the strap 5, the front horizontal portion thereof 13 being formed on its upper edge with rack teeth 14. Gearing 85 with the racks of the two plates 8 and 13 is a pinion 15, the shaft 16 of which is mounted in a strap or bracket 17 attached to the front wall of the receptacle and may be rotated by means of a knob 18 projecting 90 from the front face of the receptacle near its top. With this construction the end gage plates will be supported vertically and guided in their movements to and from the center of the machine. There is secured 95 across the front face of the receptacle contiguous to the top thereof a plate 19 that covers the racks and through which the shaft of the pinion extends.

As the adjusting pinion is rotated the end 100 gage plates are moved in and out. On one of the movable racks, preferably the lower one, there is an index pointer 20 coöperating with a scale on the front wall 10 of the receptacle. The drawings show this scale as 105 marked with the numerals 11, 10, 9, 7, 6 $\frac{1}{2}$, 6 $\frac{1}{4}$,

that indicate standard sizes of envelopes in common use. On the front of the plate 19 extending across the front of the box is secured a pad holder 21 containing a cushioning pad with which the head 22 of the envelop feeding lever 23 contacts when the latter is in elevated position.

The front wall of the receptacle terminates above the floor thereof and is cut away for accommodation of the vibrating envelop feeding lever. At the left hand side of the receptacle there is a guard plate 24 attached to gage plate 2 and extending horizontally across the front of the receptacle, below the lower edge of the front wall 10, toward the central line of the receptacle. This is to provide a sure means of holding in position small envelopes when pressed forward by the spring followers. These followers are shown as vertical rods or rollers 33 carried in suitable light frames 34.

The cam or wiper 25 located on the platen shaft and turning therewith differs from the one shown in the before mentioned application of Edward B. Hess in that its nose or feed lever operating portion 26 is pivotally mounted on the body of the cam ring so that it may be adjusted to a position radial to the axis in which it will act upon a projecting lip or lug 28 on the vertical movable arm 27 that operates the envelop feeding lever or may be turned to a position parallel to the axis of the platen in which it will not operate said arm when the platen is rotated. This is for the purpose of providing for free revolution of the platen for adjustment or other purposes without feeding an envelop from the receptacle. The adjustable nose or operating part 26 may readily be turned by the operator to either position.

The vertically movable arm 27 is guided at its lower end in an aperture in a bracket 29 and at its upper end is operatively connected to the envelop feed lever 23 by a pin and slot connection 30 between which and the pivot 31 of said lever a coiled extension spring 32 is connected to the arm and, at its lower end, to the vertically movable arm 27.

50 I claim:

1. An envelop receptacle having means for attachment to a typewriting machine, a spring follower for pressing contained envelopes toward the front of the receptacle, movable end plates and means for simultaneously adjusting the end plates toward and from the center of the receptacle to change its effective length to adapt it to envelopes of different sizes.

60 2. An envelop receptacle having means for attachment to a typewriting machine, a spring follower for pressing contained envelopes toward the front of the receptacle, movable end plates and rack and pinion means, means for simultaneously adjusting

the end plates toward and from the center of the receptacle to change its effective length to adapt it to envelopes of different sizes.

3. An envelop receptacle for a typewriting machine adapted to be mounted on the machine and having movable end plates each having a projection at the rear edge guided in a slot in the rear wall of the receptacle, a projection at the front edge guided in a slot in front wall of the receptacle, a horizontal strap projection or part extending horizontally across the front face of the receptacle such strap projections of the respective plates being arranged in different horizontal planes overlapping one another, and provided on adjacent edges with rack teeth, and a rotatable pinion located between and gearing with the sets of rack teeth, whereby the end plates may be adjusted to adapt the receptacle to envelopes of different sizes.

4. An envelop receptacle for a typewriting machine adapted to be mounted on the machine and having movable end plates each having a projection at the rear edge guided in a slot in the rear wall of the receptacle, a projection at the front edge guided in a slot in front wall of the receptacle, a horizontal strap projection or part extending horizontally across the front face of the receptacle such strap projections of the respective plates being arranged in different horizontal planes overlapping one another, and provided on adjacent edges with rack teeth, a rotatable pinion located between and gearing with the sets of rack teeth, whereby the end plates may be adjusted to adapt the receptacle to envelopes of different sizes, and an indicating device movable with one of the strap projections and coöperating indicating devices on the front of the box.

5. An envelop receptacle for a typewriting machine having means for attachment to the machine, a spring follower for pressing contained envelopes toward the front of the receptacle, end pieces movable toward and from the center of the receptacle, means for adjusting the end pieces to vary the effective length of the receptacle and a front plate against which the envelopes are pressed movable with one of the end plates and forming a partial closure for the front of the receptacle.

6. The combination with a typewriting machine of an envelop receptacle adapted to be mounted on the machine, a transversely arranged rocking lever for feeding the envelopes one by one from the receptacle to the platen of the machine, a vertical movable arm operatively connected with the envelop feed lever and serving to actuate the same, a projection thereon and a projecting member turning with the platen and adapted to strike the projection on said arm to effect

feed of an envelop once in each revolution of the platen, said projecting member turning with the platen being adjustable so that it may at will be turned into or out of operative position.

7. An envelop receptacle for a typewriting machine having means for attachment to the machine and comprising movable end plates to each of which is applied a strap 10 that projects at the rear edge of the plate and travels in a slot in the back wall of the receptacle extends forward beyond the front edge of the plate and then is disposed at right angles transversely across the front of 15 the receptacle, the part of said strap between the front edge of the plate and the transverse portion of the strap traveling in a slot in the front wall of the receptacle and the two straps being applied to the respective plates in different horizontal planes so 20 as to overlie one another with a vertical space between them.

8. An envelop receptacle for a typewriting machine having means for attachment to the machine, movable end plates each having a projection at the rear edge guided in a slot in the rear wall of the receptacle, a projection at the front edge guided in a slot in front wall of the receptacle and a horizontal strap projection or part extending horizontally across the front face of the receptacle such strap projections of the respective plates being arranged in different horizontal planes overlapping one another, and provided on adjacent edges with rack teeth and 25 means for adjusting the end plates toward and from the center of the receptacle.

In testimony whereof, I have hereunto subscribed my name.

LEWIS C. MYERS.
